FLAPPING WING TOY

William Eugene Polk, Shreveport, La.

Application October 27, 1948, Serial No. 56,683

2 Claims. (Cl. 46—118)

1

This invention relates to a toy, and more particularly to a manually operable toy that simulates a bird, bat, butterfly or other creature.

The object of the invention is to provide a toy which can be readily manually actuated to cause the wings of the toy to flap, whereby the toy will simulate a bat or other bird or creature to thereby provide a source of amusement and recreation to children.

Another object of the invention is to provide a toy which simulates a bird, bat, butterfly, or other creature, provided with moving wings, the toy of the present invention being provided with a noise maker, the toy being easily operated to provide the wings with an oscillating movement.

A further object of the invention is to provide a toy which is extremely simple and inexpensive to manufacture.

Other objects and advantages will be apparent during the course of the following description.

In the accompanying drawings forming a part of this application, and in which like numerals are used to designate like parts throughout the same:

Figure 1 is a bottom plan view of the toy of the present invention, with the cover shown in broken lines;

Figure 2 is a side elevational view of the assembly of Figure 1;

Figure 3 is a sectional view taken on the line 3—3 of Figure 2;

Figure 4 is a view similar to Figure 3, but showing the wings in raised position;

Figure 5 is a perspective view showing the frame;

Figure 6 is a sectional view taken on the line 6—6 of Figure 1;

Figure 7 is a fragmentary enlarged sectional view showing the noise maker;

Figure 8 is a view similar to Figure 7, but showing the spring of the noise maker expanded;

Figure 9 is a fragmentary sectional view showing certain constructional details of the noise maker;

Figure 10 is a sectional view taken through the pivot spring mounting;

Figure 11 is a fragmentary sectional view showing a modified form of the invention, wherein the noise maker is omitted;

Figure 12 is a plan view of another modified form of the invention;

Figure 13 is an end elevational view of the assembly of Figure 12;

Figure 14 is a perspective view of a modified frame;

2

Figures 15 and 16 are fragmentary sectional views illustrating the movement of the parts of Figure 14.

Referring in detail to Figures 1 through 10 of the drawings, there is shown a toy which is adapted to be manually actuated, and wherein the toy includes a pair of levers 30 and 31 which may be fabricated of any suitable material, such as wire. The lever 30 has one of its ends shaped

10 to define a handle portion 32, while the other lever 31 includes a similar handle portion 33, the handle portions 32 and 33 being adapted to be manually gripped for causing pivotal movement of the levers 30 and 31. The lever 30 includes a pair of sections 34 and 35, while the lever 31 includes a pair of sections 36 and 37, Figure 1. The lever 30 has its sections 34 and 35 twisted together to form an intermediate twisted section or portion 38, while the lever 31 is also provided with an intermediate twisted portion or section 39. One end of the lever 30 is straight, as at 40, while the other lever 31 also has a straight portion 41 for a purpose to be later described.

25 A spring pivot mounting is arranged between the pair of levers 30 and 31, and this spring pivot mounting is indicated by the numeral 42, Figure 10. The pivot mounting 42 includes a pair of opposed blocks 43 and 44. The block 43 is secured to the lever 30 by suitable wires or cables 46, while the other block 44 is secured to the lever 31 by similar wires 46. A spring member 45 has its ends connected to the pair of blocks 43 and 44, and the spring member 45 serves to normally urge the handle portions 32 and 33 away from each other. When the handle portions 32 and 33 are squeezed together, the handle portions pivot about the spring member 45 and assume the position shown in Figure 1. When manual pressure is released on the handle portions 32 and 33, the spring member 45 serves to urge the portions 32 and 33 apart.

35 A pair of wings 48 and 49 are provided for the toy, and the wings 48 and 49 are adapted to be flapped or oscillated upon pivotal movement of the levers 30 and 31. The wings 48 and 49 are pivotally connected to a bolt 47 which is arranged in spaced parallel relation with respect to the straight portions 40 and 41. The wing 48 includes a pair of arms 50 and 51 that may be fabricated of any suitable material, such as wire, and formed integrally with the arms 50 and 51 is a web 52. Arranged between the pair of arms 50 and 51 is a brace 53, and an end portion 54 of the arm 51 is bent angularly with respect to

the main portion of the arm 51 and secured to the brace 53. The brace 53 is shaped to provide an eyelet 55, and a portion 56 of the lever 30 is shaped arcuately to define a guide member for slidably projecting through the eyelet 55.

The arm 50 is shaped to provide a coil 57, while the brace 53 is also provided with a coil 58, the coils 57 and 58 pivotally engaging the rod 47. Extending from the coil 57 is an offset section 59, while extending from the coil 58 is an offset section 60, the sections 59 and 60 being interconnected together by a link 61 which is arranged contiguous to the straight portion 41. The link 61 is provided with a pair of coils 63 and 62 which pivotally engage the straight portion 41.

The other wing 49 has a construction that is similar to the wing 48, and the wing 49 includes a pair of arms 64 and 65 that are interconnected together or have formed integrally therewith a web 67, there being a brace 68 arranged in between the arms 64 and 65. The brace 68 is provided with an eyelet 69 through which slidably projects a guide member 70 that extends from the lever 31. The arm 64 is provided with a coil 71 which rotatably engages the rod 47, and an offset portion 73 connects the coil 71 to a link 72 that has coils 28 and 29 engaging straight portion 40. The brace 68 is provided with a coil 74 that rotatably or pivotally engages the rod 47, and an offset portion 75 connects or extends from the coil 74 to the link 72.

Extending over the wings 48 and 49 is a cover 76 which may be fabricated of any suitable material, such as crepe paper or flexible cloth. The cover 76 may be shaped so that its external configuration conforms in shape to the wings of a butterfly, bat or other creature. The cover 76 is shown in broken lines in Figure 1, but in solid lines in Figures 3 and 4.

Connected to the toy of the present invention is a noise maker which is shown in detail in Figures 7 and 8. The noise maker includes a spring 77 that has one end 78 connected to the twisted portion 38 of the lever 30. The coil spring 77 extends below or through an arcuate guide member 79, so that as the levers 30 and 31 are pivoted back and forth, the spring 77 will engage the guide member 79, whereby a noise will be emitted, whereby the toy will be more realistic.

Referring to Figure 11 of the drawings, there is shown a slightly modified form of the invention, wherein the noise maker is omitted. Thus, in Figure 11 a coil spring 80 has one of its ends 81 arranged in engagement with the twisted portion 39 of the lever 31, while the other end 82 of the spring 80 is arranged in engagement with the twisted portion 38 of the lever. The spring 80 serves to augment the effect of the spring 45 when large toys are used.

Referring to Figures 12 and 13 of the drawings, there is shown another modified form of the invention, wherein the toy is indicated by the numeral 83. The toy 83 includes a pair of oscillating wings 84 and 85 that may be fabricated of any suitable rigid material, such as wood. The levers 30 and 31 are again provided for causing oscillation of the wings 84 and 85, there being an opening 86 in the wing 84 for the projection therethrough of the guide member 56. Similarly, the wing 85 is provided with an opening or hole 87 for the projection therethrough of the other guide member 70. Secured to one side of the wing 84 is a bracket 88, the bracket 88 being secured to the wing 84 by suitable securing elements, such as screws 89. The bracket 88 is pro-

vided with coils 90 which rotatably engage the rod 47, and the bracket 88 is further provided with coils 91 that rotatably engage the straight portion 41 of the lever 31. The bracket 92 is secured to the other wing 85 by screws or other securing elements 89, and the bracket 92 includes coils 93 that rotatably engage the rod 47, there being a second pair of coils 94 on the bracket 92 for rotatably engaging the straight portion 40 of the lever 30. Hence, upon actuation of the handle portions 32 and 33, the wings 84 and 85 will be caused to flap or oscillate. It will be noted that the front portions of the wings 84 and 85 coact to form a head which resembles the head of a creature.

Referring to Figures 14, 15 and 16 of the drawings, there is shown another modified form of the toy of the present invention. Only a portion of the toy is shown, and the mechanism shown in Figures 14, 15 and 16 is adapted to be used in lieu of the mechanism shown in Figure 5. By using the assembly of Figures 14 through 16, upon movement of the handle portions 32 and 33 toward each other, the wings 48 and 49 will be lowered instead of being raised, as is the case with the assembly of Figure 5. The assembly shown in Figures 14 through 16 includes a bracket 95 that comprises an arm 96 and a brace 97, there being coils 98 arranged on the bracket 95 for rotatably engaging the rod 47. A second pair of coils 99 are provided on the bracket 95 for rotatably engaging the straight portion 41 of the lever 31. The bracket 95 is adapted to be secured in any suitable manner to a wing, such as the wing 49.

A second bracket 100 includes a brace 101 and an arm 102, and the bracket 100 also includes a pair of coils 103 that rotatably engage the rod 47, there being a second pair of coils 104 on the bracket 100 for rotatably engaging the straight portion 40 of the lever 30.

In use, a child grips the handle portions 32 and 33 in the hands and moves the handle portions toward each other. As seen in Figures 1 through 10, as the handle portions 32 and 33 are moved toward each other, the levers 30 and 31 will pivot about the spring mounting 42 so that the straight portions 40 and 41 will move away from each other. This will cause the wings 48 and 49 to move downwardly from the position shown in Figure 4 to the position shown in Figure 3. Upon release of pressure on the handle portions 32 and 33, the spring 45 will cause the wings to move from the position shown in Figure 3 to the position shown in Figure 4, and upon continuation of this operation the wings will be caused to oscillate or flap.

Referring to Figures 7 and 8 and 9, it will be seen that as the levers 30 and 31 pivot back and forth, the spring 77 will rub against the guide member 79, whereby a noise will be emitted. Thus, the toy will have a realistic sound as well as a realistic appearance. In Figures 12 and 13 there is shown a modified form of the apparatus, wherein the wings 84 and 85 are made of a rigid material, and these wings will be caused to oscillate or flap upon pivotal movement of the levers 30 and 31. In Figures 14 through 16, there is shown a modified portion of the framework, 70 wherein the wings will flap or oscillate in the opposite direction from that shown in Figures 1 through 10. Thus, the assembly shown in Figure 14 is adapted to be used in lieu of the assembly shown in Figure 5, so that when the handle portions 32 and 33 are moved toward each other,

the wings will initially move from a down position to an up position. Then, when the pressure on the handle portions 32 and 33 is released, the wings will resume their lower position.

The toy of the present invention can be simply and inexpensively manufactured, and the various swivel joints can be made by twisting wire into an eye-type bearing surface at the desired point. Further, in lieu of using wire, ribbon material may be used, and the spring 45 serves to maintain the levers 30 and 31 immobile until a manual force is applied to the handles 32 and 33. The coil spring 80 is advantageous when larger models of the toy are being used, as when added tension is required in the operation of the toy. This framework may be shaped to resemble birds, bats, butterflies and the like, and fanciful ornaments or objects may be painted on the wings. Further, an electrically operated mechanism can be provided for causing oscillation of the wings.

What is claimed is:

1. In a toy having the external configuration of a creature, a pair of levers each provided with a handle on one end thereof, a spring mounting arranged between said levers, said spring mounting comprising a pair of blocks secured to said levers, a spring member connecting said blocks together and normally urging said handles away from each other, a rod arranged in spaced parallel relation with respect to the other ends of said levers, a first and second wing mounted for oscillatory movement, said first and second wings each including a frame fabricated of wire shaped to define a pair of arms having one end interconnected together by a web, a brace extending between said pair of arms, the brace of one wing being arranged in alignment with the brace of the other wing, a portion of one of said arms extending angularly with respect to the main portion thereof and secured to said brace, said other arm and said brace each being provided with a coil pivotally engaging said rod, said coils terminating in offset portions, a link extending be-

tween said offset portions and provided with a pair of coils pivotally engaging one of said levers.

2. In a toy having the external configuration of a creature, a pair of levers each provided with a handle on one end thereof, a spring mounting arranged between said levers, said spring mounting comprising a pair of blocks secured to said levers, a spring member connecting said blocks together and normally urging said handles away from each other, a rod arranged in spaced parallel relation with respect to the other ends of said levers, a first and second wing mounted for oscillatory movement, said first and second wings each including a frame fabricated of wire and shaped to define a pair of arms having one end interconnected together by a web, a brace extending between said pair of arms, the brace of one wing being arranged in alignment with the brace of the other wing, a portion of one of said arms extending angularly with respect to the main portion thereof and secured to said brace, said other arm and said brace being provided with a coil pivotally engaging said rod, said coils terminating in offset portions, a link extending between said offset portions and provided with a pair of coils pivotally engaging one of said levers, and a spring member defining a noise maker.

WILLIAM EUGENE POLK.
